UNITED STATES PATENT OFFICE.

GEORGE H. RICKE, OF CINCINNATI, OHIO.

RAIL-JOINT.

1,240,092.

Specification of Letters Patent. Patented Sept. 11, 1917.

Application filed April 23, 1917. Serial No. 163,942.

To all whom it may concern:

Be it known that I, GEORGE H. RICKE, a citizen of the United States, residing at Cincinnati, in the county of Hamilton and 5 State of Ohio, have invented certain new and useful Improvements in Rail-Joints; and I do declare the following to be a full, clear, and exact description of the invention, such as will enable others skilled in the art to 10 which it appertains to make and use the same.

This invention relates to improvements in rail joints and more particularly to those in which parts are welded together.

15 An object of the invention is to provide a simple, inexpensive and effective rail joint by means of which the meeting ends of the rails are not only firmly held together while allowing for expansion and contraction, but 20 the rail ends are so engaged by the fish plates and locking plate that the joint will be prevented from breaking downward and the rails will always be held on a level and in longitudinal alinement with each other.

25 Another object is to provide a method whereby the parts may be readily assembled and securely held in position.

Other objects will appear as the description proceeds.

30 Like reference numerals are used throughout the several views to designate corresponding parts.

Figure 1 is a perspective view of the slotted rail;

35 Fig. 2 is a perspective view of the fish plate;

Fig. 3 is a perspective view of the locking plate 5;

40 Fig. 4 is a sectional perspective view of the joint;

Fig. 5 is a perspective view of the locking plate 6 inverted; and

Fig. 6 is a side elevation showing the joint in locked position.

45 The rails 1 are provided with transverse slots or openings 2 formed in the extreme ends of their web portions. Fish plates 3 are placed on the opposite sides of the rails 1 and have slots or openings 4 which register with the opening in the said rails.

In order to hold the rails and fish plates together, I provide locking plates 5 which are inserted from opposite sides of the rails and which have shoulders 6 vertical thereto 55 and extending the length of said fish plates,

These plates 5 are substantially right angular in end elevation. The length of the transverse slot 2 formed by the abutting ends of the rails 1 is slightly greater than that of the horizontal portion of the plate 5. 60 This difference or space 7 is left to allow for the expansion or contraction of the rails due to different weather conditions. One of the locking plates 5 is formed with its vertical side extending downwardly and 65 against the side of one fish plate and the other locking plate has its vertical side extending upwardly and on the outside of the other fish plate. While the drawings show the vertical sides of the locking plates extending to the ends of the fish plates, it will 70 be seen that they may be shortened to the length of the slots and serve their purpose equally well.

In making the joint I first place the rails 75 1 in alinement, thereby forming a slot 2. Next the fish plates 3 are placed on each side of the rails so that the openings 4 therein will register with the openings 2 in the rails. The horizontal locking plates 5 are then inserted 80 through the openings from each side so that the vertical shoulders or flanges 6 will abut against the outer side of the fish plates 2.

When the parts of the joint are in position, a welded joint is formed connecting the exposed portions at 8 of the locking plates 5 on the opposite sides of the rails 1, leaving the rails free of said plates. The vertical flanges 6 of the locking plates 5 should 90 project beyond the ends of the slots in the fish plates 3 and outwardly to the edges of said fish plates and are united together in a welded joint 9.

In operation it will be seen that my improved method consists in forming abutting rails with transverse slots, and then placing slotted fish plates on opposite sides of the said abutting rails, after which I insert shouldered locking plates through 100 the slots of the fish plates and rails from opposite sides thereof and then weld the plates together either at point 9 or 8 or both, as before described.

It will be seen that I have made an improved rail joint which will not require any bolts to hold the rails together, and which will also compensate for expansion and contraction due to different weather conditions.

Various changes in the form, proportion 110

and the minor details of construction may be resorted to without departing from the principle or sacrificing any of the advantages of the claimed invention.

5 I claim:

1. The combination of the abutting ends of two track rails having transverse openings, a pair of plates having shoulders, said plates passing through said rail openings 10 from opposite sides, said shoulders limiting the transverse movement of the plates, and a welded joint connecting the two plates but leaving them free of the rails.
2. The combination of the abutting ends 15 of track rails having transverse slots, a pair of plates of right-angularly shape in cross section having their horizontal portions passed through said slot from opposite sides of the rail, the horizontal portions of said 20 plate being of less length than the rail slot to allow for expansion and contraction of the rail, and a welded joint connecting the exposed portions of the plates on opposite

sides of the rail but leaving the rails free 25 of said plates.

3. The combination of the abutting ends of track rails having transverse slots therein, fish plates on opposite sides of the rails having slots alining with those in the rail, a pair of locking plates of right angular 30 shape in cross section having their horizontal portions projected through said alined slots from opposite sides of the rails and having their vertical portions in contact with the outer faces of the fish plates, said 35 vertical flanges of the locking plates being projected beyond the ends of the slots in the fish plates, and a welded joint uniting said vertical portions to the fish plates.

In testimony whereof I have hereunto set 40 my hand in the presence of two subscribing witnesses.

GEORGE H. RICKE.
